UNITED STATES PATENT OFFICE.

ADDISON JENKINS, OF KOKOMO, INDIANA, ASSIGNOR TO D. C. JENKINS GLASS CO., OF KOKOMO, INDIANA, A CORPORATION.

DESIGN FOR AN ASH TRAY.

Application filed October 18, 1926. Serial No. 19,399. Term of patent 7 years.

To all whom it may concern:

Be it known that I, ADDISON JENKINS, a citizen of the United States, and a resident of the city of Kokomo, county of Howard, and State of Indiana, have invented a new, original, and ornamental Design for Ash Tray, of which the following is a specification, reference being had to the accompanying drawings, forming a part thereof.

In the drawings, Fig. 1 is a plan view of the article showing my new design. Fig. 2 is a central vertical section on the line 2—2 of Fig. 1.

I claim:

The ornamental design for an ash tray, as shown.

ADDISON JENKINS.
